(57) **CLAIM**

The ornamental design for automatic external defibrillator battery pack, as shown.

DESCRIPTION

FIG. 1 is a perspective upper view of an automatic external defibrillator battery pack showing my design;
FIG. 2 is a perspective bottom view thereof;
FIG. 3 is a right side view thereof;
FIG. 4 is a top view thereof;
FIG. 5 is front view thereof;
FIG. 6 is a rear view thereof;
FIG. 7 is a left side view thereof; and,
FIG. 8 is a bottom view thereof.
